UNITED STATES PATENT OFFICE.

GEORGE SCHNEIDER, OF AUGUSTA, KANSAS.

CAR-COUPING.

SPECIFICATION forming part of Letters Patent No. 616,363, dated December 20, 1898.

Application filed January 3, 1898. Serial No. 665,405. (No model.)

To all whom it may concern:

Be it known that I, GEORGE SCHNEIDER, a citizen of the United States, residing at Augusta, in the county of Butler and State of Kansas, have invented certain new and useful Improvements in Car-Couplers; and I do hereby declare the following to be a full, clear, and exact description of the invention, such as will enable others skilled in the art to which it appertains to make and use the same.

My invention relates to car-couplers; and its object is to provide an improved construction of the same, by means of which two cars provided with the ordinary link and pins will be automatically coupled as two cars come together.

The invention consists in the novel construction and combination of parts hereinafter fully described and claimed.

In the accompanying drawings, Figure 1 is an elevation showing two cars provided with my improvements. Fig. 2 is an end view of one of the cars. Fig. 3 is a detail perspective view of one of the link-holding plates and spring-arms. Fig. 4 is a similar view of one of the vertically-movable yokes which carry the coupling-pins.

In the said drawings the reference-numeral 1 designates the cars, each provided with a draw-head 2, 3 designating the coupling-link and 4 the coupling-pins. As the coupling devices of each car are identical in construction a description of one will suffice for both.

Secured to the under side of the draw-head 35 is an outwardly-extending curved spring-arm 6^a, to the outer end of which is secured a plate 5 in alinement with the mouth of the draw-head and provided with two lugs 6, which serve to hold the link on said plate in 40 coupling. The numeral 7 designates an arm, also secured to the draw-head, having a hook at its outer end, which engages with the arm 6^a and holds it in position. The pin 4 is of the ordinary construction and passes through 45 a hole 8 in a vertically-movable plate 9, formed integral with a yoke 12. This plate is provided with two lugs 11, which are bent over the head 10 of the pin and securely hold the latter to the plate. The yoke 12 is formed 50 with two alined holes 13, through which passes a vertical rod 14, secured to the car and acting as a guide for the said yoke. Se-

cured to said yoke is an eye 15, with which is connected one end of a short chain 16, the other end of which is connected with the horizontal arm 17 of a vertically-movable lifting rod 18, passing through a guide-plate 19, secured to the car. The lower end of this rod 18 is bent laterally outward, forming a horizontal arm 20. The arm 17 is provided with 55 an eye 21, which works upon the rod 14, which forms a guide therefor. Secured to the car at one side of the draw-head is a bent rod 22, around the horizontal portion of which is coiled a rod 26, the outer end of which is inclined downwardly, forming an arm 24, while 60 the other or inner end is extended backwardly, forming an arm 27, which engages under the inner end of the rod 22.

As before stated, the coupling devices of an 70 adjoining car are similar in construction to those above described; but the rod 26 and the lifting rod 18 of one car are at the opposite side of the draw-head of the other car.

The operation is as follows: In normal position the pins 4 are lowered, as seen in Fig. 1, and as two cars approach each other a coupling-link is inserted in the draw-head of one car, the inner end abutting against the pin and the outer end supported by the plate 5. 75 As the cars come together the outer end of the link will slide onto the opposite plate 5 and at the same time the inclined rods 24 will engage with the lifting plates 20, raising the same, and through the connections elevating 80 the yokes 12 and the pins 4, so as to allow the link to pass into the draw-heads. By this time the lifting plates will have passed back of or past the inner ends of the rods 24, when they will fall down, so that the coupling-pins will also fall down and engage with 85 the link. 90

For the purpose of uncoupling the cars I provide the following means: Secured to the end of the yoke 12 are eyes 27^a and 28, and 95 connected with the eye 27^a is a chain 29, leading to a hand-bar 30, working in the guide-eye 31 of the rod 14, and by which the pin 4 may be elevated from the top of the car. To the eye 28 is secured a chain 32, fastened to 100 the arm 33 of a rock-shaft 34, journaled to the car and provided with a crank 35, so that the coupling-pin may be elevated from the side of the car. The rod 24 is journaled to

the rod 22 by means of the coils, so that in uncoupling it will give or turn, so as to allow the lifting plate 20 to be elevated.

Having thus fully described my invention,
5 what I claim is—

1. In a car-coupler, the combination with the draw-head, the coupling-pin passing therethrough, the vertically-movable yoke carrying said pin, the chain connected with 10 said yoke, the horizontal arm 17 to which the other end of said chain is connected, the vertical lifting rod bent at its lower end and adapted to be raised by means carried by an approaching car, of the curved spring-arm 15 secured to the draw-head, the plate at the outer end provided with lugs and the hooked holding-arm, substantially as described.
2. In an automatic car-coupling, the com-

bination with the cars, the draw-heads, the pins passing therethrough, the vertically-movable yokes carrying said pins, the lifting rods connected with said yokes, said rods being bent at the lower ends thereof, the curved spring-arms and the link-supporting plates at the upper ends thereof provided with lugs, 25 of the bent rods secured to the cars, the rods coiled thereon having the outer ends inclined downwardly and the inner ends engaging with the inner ends of said bent ends, substantially as described.

In testimony whereof I affix my signature in presence of two witnesses.

GEORGE SCHNEIDER.
